UNITED STATES PATENT OFFICE

116,053

DESIGN FOR A COMBINED REAR VIEW MIRROR AND SUPPORT THEREFOR

Oliver C. Ritz-Woller, Chicago, Ill.

Application November 14, 1938, Serial No. 81,078

Term of patent 14 years

To all whom it may concern:

Be it known that I, Oliver C. Ritz-Woller, a citizen of the United States, residing at Chicago, in the county of Cook and State of Illinois, have invented a new, original, and ornamental Design for a Combined Rear View Mirror and Support Therefor, of which the following is a specification, reference being had to the accompanying drawing, forming part thereof.

This application is a continuation in part of my copending application Serial No. D-78,607, filed July 20, 1938.

In the drawing:

Fig. 1 is a front elevational view of a combined rear view mirror and support therefor embodying my new design;

Fig. 2 is a rear elevational view thereof;

Fig. 3 is a side elevational view thereof; and

Fig. 4 is an end elevational view thereof looking from the line 4—4 of Fig. 3.

I claim:

The ornamental design for a combined rear view mirror and support therefor, substantially as shown.

OLIVER C. RITZ-WOLLER.
